BOLT ACTION FOR A RIFLE

Jerry D. Haskins, Enid, Okla., assignor to Champlin-Haskins Incorporated, Enid, Okla., a corporation of Oklahoma

Filed May 13, 1968, Ser. No. 11,895

Term of patent 14 years

Int. Cl. D22—01

U.S. Cl. D22—7

FIGURE 1 is a side elevational view of a bolt action for a rifle embodying my new design.

FIGURE 2 is an elevational view of the bolt action for a rifle illustrated in FIGURE 1, but showing the action as it appears when viewed from the side opposite that appearing in FIGURE 1.

FIGURE 3 is a front view of the bolt action for a rifle depicted in FIGURES 1 and 2.

FIGURE 4 is a rear end view of the bolt action for a rifle depicted in FIGURES 1 and 2.

FIGURE 5 is a bottom view of the bolt action for a rifle depicted in FIGURES 1 and 2.

FIGURE 6 is a top plan view of the bolt action for a rifle depicted in FIGURES 1 and 2.

I claim:

The ornamental design for a bolt action for a rifle, as shown.
